UNITED STATES PATENT OFFICE.

HENRY S. SCHOPF, OF SPOKANE, WASHINGTON.

COOLER.

1,386,900.

Specification of Letters Patent. Patented Aug. 9, 1921.

Application filed December 9, 1920. Serial No. 429,374.

To all whom it may concern:

Be it known that I, HENRY S. SCHOPF, a citizen of the United States, residing at Spokane, in Spokane county, and State of Washington, have invented certain new and useful Improvements in Coolers, of which the following is a specification.

My present invention relates to improvements in evaporative coolers especially adapted for domestic use in refrigerating and preserving foods and other provisions in a sanitary condition.

The primary object of the invention is the production of a device of this character of 15 the knockdown type which may be folded in compact form for shipping or storage, and which when erected or assembled for use will sustain and support the water bags or containers forming the inclosure for the 20 foods or provisions. In carrying out my invention I utilize a plurality of double wall devices or receptacles in connection with sustaining frames, which latter are foldable into compact shape and are constructed in 25 such manner as to afford convenience in erection and packing.

The invention consists essentially in certain novel combinations and arrangements of parts involving the supporting or sustaining 30 frames and water receptacles as will hereinafter be more clearly set forth and claimed.

In the accompanying drawings I have 35 illustrated one complete example of the physical embodiment of my invention in which the parts are combined and arranged according to the best mode I have thus far devised for the practical application of the principles of my invention.

40 Figure 1 is a sectional, transverse, vertical, view of a cooler embodying my invention.

Fig. 2 is a perspective view of the supporting frame, detached.

In the preferred form of my invention I 45 utilize a metallic tank A, forming the base of the device, and receptacle to receive dripping water, which is open at the top, provided with a suitable drain outlet (not shown) and preferably rectangular in shape.

50 A similar vessel B forms the top of the device and is fashioned as a pan, preferably of metal, inverted, conforming to the shape of the base tank, but smaller in dimensions than the base tank in order that 55 water may drip or drop from the lower edges of the inverted pan to the base tank which

forms a reservoir or receiver for the dripping water from the cooler.

On top of the metallic top of the cooler I locate a water container C, of fabric or similar material of such porosity as to permit water to pass through its pores in the desired quantity, and as shown this container is flat, rectangular in shape and of less dimensions than the metal top B. The container C may be filled through the filling spout C' and the contained water slowly seeps or percolates through the porous walls thereof, a portion being evaporated and the remainder falling to the reservoir, over the 70 top edges of the metal top B.

The sides of the cooler, whether considered as sides, or sides and ends, are constituted by an open, rectangular receptacle or container D which is made up of a single element with double walls, and single top and bottom members, forming an annular water chamber that may be filled through the opening D'. In addition to these containers, a third container E is utilized, resting on top 80 of the reservoir, or rather supported directly above the reservoir, as will be described, and within the confines of the rectangular open container D. These three containers are made of material to form substantial vessels for retaining the water, and their several walls are of the required porosity to permit the water to ooze or seep therethrough, and the evaporation of this water provides for exchange of heat, rendering the temperature of the air within the 85 inclosure formed by the several containers, at a comparatively low degree with relation to the surrounding atmosphere.

For supporting the water containers I 95 utilize a frame indicated as a whole by the letter F in Fig. 2, and this frame, involving an inner and outer section, holds in erect, vertical position the open, rectangular container D, sustains the metal top B and top 100 container C, and also supports the bottom container E.

Both sections of the frame are made up of wire, the parts being bent to shape by proper tools or machinery, and the wire is 105 of proper gage to afford strength and stability for the performance of the functions of the frame sections.

The outer frame section is designed to enclose the open rectangular container D, and 110 its two side walls and end walls are adapted to fold down upon the bottom, while the in-

ner section of the frame is of a size to fit within the interior of the open rectangular container, thus affording support for the vertical, double walled, sides and ends of the 5 container. The inner section, also, has foldable sides and ends in order that it may be "knocked down" with the outer section, and then both sections folded into compact form, and packed with the collapsed or deflated 10 containers between the top and bottom metal portions of the cooler.

The wire base of the main or outer section of the frame is composed of parallel side bars 1 and parallel end bars 2, and each of 15 these members has downturned ends 3, secured in pairs by a clamp ring 4, to form legs at the four corners of the base, the floor of the base being fashioned of cross wires 5 with their ends coiled or tied about the side 20 bars of the base.

The sides and ends of the outer frame are foldable, and may be laid flat on the base, for packing or storing when the cooler is not in use. The sides each have a top bar 6 and the 25 ends each have a corresponding top bar 7, while the sides, at 8 are hinged to the side bars 1 of the base, and are provided with longitudinally extending brace bars 9, each having an eye 10 at its extremities, and tied 30 to the end vertical bars 11 of the sides.

The foldable ends of the outer frame have vertical posts 12 and longitudinal or horizontal brace bars 13, and are hinged at 14 to the end bars 2 of the base. The ends also 35 have eyes 15 at the extremities of the horizontal brace bars 13, and the eyes 10 and 15 of the sides and ends are alined, and disposed in pairs, to receive the vertical locking bars 16, one at each corner of the frame. These 40 locking bars each have an upper bent end 17 to prevent slipping entirely through the eyes, and the bars are located at the corners of the frame to tie the respective sides and ends of the frame together. They may readily 45 be withdrawn to disconnect the frame members, after which the members may be folded down on top of the frame base for packing.

Within the outer frame a second frame is 50 inclosed, which latter frame is of course smaller in its dimensions, but its rectangular bottom 18 is elevated above the bottom of the outer frame and its corner legs 19, passing through the bottom of the lower frame 55 rest upon the base A of the cooler. The foldable sides 20 of the inner frame are hinged at 21 to the bottom, and the similarly foldable ends 22 are hinged to the bottom at 23. The sides and ends of the inner frame are 60 provided with a pair of top hooks 24, extending outwardly, and adapted to engage over the complementary top bars of the sides and ends of the outer frame, to provide a rectangular space between the outer and inner frames for the accommodation of the 65

rectangular water container of the cooler. The bottom of the inner frame forms the bottom of the cooler, and at 25 the vertical brace bars 25' of the inner frame members are offset or bent to form supporting lugs 70 for a horizontally disposed shelf 26, of the cooler.

From the above description it will be apparent that I have provided a device of this character that may be erected with facility 75 and despatch, the parts being assembled and built up from the base pan or tank A as shown in the drawings. With the containers filled to required capacity with water, the operation will be understood, as it is apparent that the water oozing through the porous walls of the container to the exterior surfaces thereof, is evaporated by air currents, thus exchanging and carrying off the heat units, to cool the interior of the device. 80 85

The containers form a well protected enclosure for provisions or food, and the porosity of the walls of the containers permits passage of the water therethrough to provide moisture on the outer surfaces of the containers at all times, as long as the supply of water lasts. From the top container C the water drips or drops and flows down the exterior walls of the rectangular container D, part being evaporated and the remainder 90 finally reaching the tank or pan A. The water in the container D also oozes through its walls, and the portion not evaporated is recovered in the base pan A.

Preferably the containers are emptied before dismantling, and after the containers have been made ready for packing, the frames may be knocked down and folded into compact form for storing or shipping.

Having thus fully described my invention, 100 what I claim as new and desire to secure by Letters Patent is—

1. The combination with an open base pan and containers as described, of a supporting frame comprising inner and outer sections and each section formed with a bottom portion for the purpose described, said sections having foldable sides and ends, means for locking the sections of the frame, and means for locking the sides and ends of the outer section.

2. The combination with a base pan and containers as described, of inner and outer frame sections each having a rigid bottom, the sides and ends of said sections being foldable on their respective bottoms, means for locking the sides and ends of the outer section together, and means on the inner section to engage the outer section for holding the former in fixed position.

3. The combination with containers as described of a supporting frame comprising inner and outer sections each having a rigid bottom and foldable ends and sides, of alined eyes at the corners of the outer section and

corner locking bars therefor, and hooks on the inner section adapted to engage the outer section, for the purpose described.

4. In a cooler as described, the combination with inner and outer frame sections having rigid bottoms, and a base pan, of a rectangular water container between said sec-

tions and a bottom container supported on the bottom of the outer section, a top member closing the cooler of less dimensions than the base pan, and a water container on said top member, as described. 10

In testimony whereof I affix my signature.

HENRY S. SCHOPF.
